UNITED STATES PATENT OFFICE.

JEREMIA KANTER, OF PHILADELPHIA, PENNSYLVANIA, ASSIGNOR TO MAX MARCOUSE, OF PHILADELPHIA, PENNSYLVANIA.

BUTTON.

1,118,555.

Specification of Letters Patent. Patented Nov. 24, 1914.

Application filed December 2, 1913. Serial No. 804,182.

To all whom it may concern:

Be it known that I, JEREMIA KANTER, a citizen of the United States, residing at Philadelphia, in the county of Philadelphia and State of Pennsylvania, have invented certain new and useful Improvements in Buttons, of which the following is a specification.

My invention relates to improvements in buttons, the object of the invention being to provide a covered button which dispenses with the ordinary shank or tab for attachment to the goods, and permits the button to be sewed directly through the fabric of the button to attach the same to the goods, and thereby permit such buttons to be sewed by a machine as well as by hand.

Heretofore fabric covered buttons have been provided with some sort of projecting shank or tab which is sewed to the goods by stitches transversely through the shank or tab, and such sewing cannot be effectually done with the sewing machine. Furthermore, this construction of button projects the button beyond the surface of the goods farther than is desirable in many cases, and the button is expensive to manufacture by reason of its many parts and the necessary amount of labor in assembling the same.

It is the purpose of my invention to provide a button which will overcome the objections to buttons as heretofore made, which will reduce the cost of manufacture, and which is capable of considerable modification to provide buttons to suit the varying taste of the trade.

With these and other objects in view, the invention consists in certain novel features of construction and combinations and arrangements of parts as will be more fully hereinafter described and pointed out in the claims.

In the accompanying drawings: Figure 1 is a plan view illustrating a preferred form of my improved button. Fig. 2 is a view in section on the line 2—2 of Fig. 1. Fig. 3 is an inverted perspective view of the outer metal ring. Fig. 4 is a perspective view of the inner metal ring. Fig. 5 is a view similar to Fig. 2 illustrating a modification, and Fig. 6 is a view similar to Figs. 2 and 5 illustrating another modification.

Referring to my improved button illustrated in Figs. 1, 2, 3, and 4, 1 represents an outer metal ring, and 2 an inner metal ring which coöperate to secure a fabric covering 3 in position as will now be explained. The outer button 1 is of general truncated conical shape having at its larger end, an inwardly projecting annular flange 4. Around this ring 1, a double thickness of fabric 3 is positioned with its edge bent inside of the flange 4. The inner ring 2 is of truncated conical form but the angle of the cone is appreciably less than that of the outer ring as clearly shown in Fig. 2. The inner ring 2 has a backwardly projecting flange 5 and a sheet 6 of flax or other strong fabric is positioned over the smaller end of the inner ring 2 with its edges preferably confined under the flange 5.

The ring 2 is forced inside of ring 1 so that the adjacent edges of the flanges 4 and 5 coöperate to clamp the inwardly bent edges 7 of the fabric 3, and bind the latter in place. This clamping action also clamps the edges of the fabric 6, so that all of the fabric is clamped securely by the two rings 1 and 2.

It will be noted that the two conical rings 1 and 2 have their smaller ends in substantial alignment, so that the fabric thicknesses 3 and 6 extend across the open ends of the rings. It is my intention to sew the buttons to the goods by stitching directly through these thicknesses of fabric, so that I can dispense altogether with the necessity for an attaching shank or tab.

In Fig. 5, I illustrate a modification in which I employ an outer ring 1 similar to that disclosed in the preferred form, in combination with an inner ring 8 which differs in shape from ring 2. This ring 8 is of general cylindrical form with an inwardly projecting annular flange 9 at its outer end. The ring 8 is forced into ring 1 and binds the edges of the fabric 3 against the inner edge of ring 1. In Fig. 6, I illustrate what is known as a combination button, that is, a button which employs two different colors or pieces of fabric, to permit the various combinations to suit the gown on which the buttons are used. In this construction of button, I employ an inner ring 10 of general conical form with an outwardly curved flange 11 at its larger end adapted to clamp 110

within the outer ring 12 which is also of conical form, but reversely positioned, and at one end is provided with an inwardly projecting curved flange 13. The outer ring 12 is covered by a fabric sheet 14, and the inner ring 10 is covered by a fabric sheet or sheets 15, the edges of the latter clamped between the inner and outer rings as clearly shown. This enables one color or fabric to be provided around the outer ring and another over the inner ring so that a combination of colors is had. In this modification illustrated in Fig. 6, I preferably locate a washer 16 of paper under the fabric so as to secure a firm gripping action when the rings are pressed together.

In all forms of the invention, it is of course to be understood that the inner ring and the outer ring are of such diameter that when pressed together, they will exert a firm gripping action on the fabric, and the latter will be securely held in position so that it may be sewed directly to the goods and constitute the sole attaching means of the button with the goods.

Various other slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A button comprising two truncated conical rings having their smaller ends located in juxtaposition, and a sheet of flexible material located between the rings and extending over the opening in the inner ring, substantially as described.

2. A button comprising two truncated conical rings having their smaller ends located in juxtaposition, and a sheet of flexible

material located between the rings and extending over the opening in the inner ring, and a fabric covering inclosing the outer ring, substantially as described.

3. A button comprising an inner truncated conical ring, a flexible sheet secured over the smaller end of said ring, an outer ring of truncated conical shape positioned over the flexible sheet and having an inwardly projecting flange at its larger end, a fabric sheet positioned over the outer ring, and the free edge of said fabric clamped between the rings, substantially as described.

4. A button comprising an inner truncated conical ring having a backwardly bent flange at its larger end, a flexible sheet secured over the smaller end of said ring, the free edges of said sheet clamped under the said annular flange, the outer ring of truncated conical shape having an inwardly projecting flange at its larger end, a fabric sheet positioned over the outer ring, and the free edge of said fabric clamped between the rings, substantially as described.

5. A button comprising two truncated conical rings having their smaller ends located in juxtaposition, and a fabric covering over the outer ring with its edges clamped between the rings, substantially as described.

6. A button comprising two truncated conical rings having their smaller ends located in juxtaposition, a flexible sheet interposed between the rings and extending across the smaller end of the inner ring, and a second flexible sheet covering the outer ring with its edges clamped between the rings, substantially as described.

In testimony whereof I have signed my name to this specification in the presence of two subscribing witnesses.

JEREMIA KANTER.
